F. MANKEY.

PANEL.

No. 17,117.

Patented Feb. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,117, dated February 15, 1887.

Application filed December 30, 1886. Serial No. 223,060. Term of patent 7 years.

To all whom it may concern:

Be it known that I, FREDERICK MANKEY, of Williamsport, Lycoming county, Pennsylvania, have invented and produced a new and 5 original Design for Panels, of which the following is a specification.

My design is shown in the accompanying photograph, forming part of this application; and it consists in the raised parallelogram A, 10 having rounded edges B. Adjacent to said parallelogram is a channel, C. Parallel to each side of said parallelogram is a rounded bead, D. At the corners of the design and between the ends of the beads are elevations E, having 15 rounded upper surfaces. Between said eleva-

tions and extremities of the beads are channels, as F. Upon the surface of the parallelogram A appears a series of parallel rounded beads, G.

I claim—

The design for a panel, substantially as herein shown and described, which consists in the raised parallelogram A, having rounded edges B, channels C, beads D, elevations E, channels F, and parallel beads G.

FREDERICK MANKEY.

Witnesses:

C. F. MANKEY,
LEONHARD KNAUSS.
